United States Patent

Des. 238,521

Patented Jan. 27, 1976

238,521

BIB

Karl Gösta Bertil Andersson, Halmstad, Sweden, assignor
to Duni Bila AB, Halmstad, Sweden

Filed Mar. 22, 1974, Ser. No. 453,864

Term of patent 7 years

Int. Cl. D2—02

U.S. Cl. D2—229

FIG. 1.

FIG. 2.

FIG. 3.

FIG. 4.

FIG. 1 is a front perspective view of a bib showing my new design, in a flat position;

FIG. 2 is a rear perspective view of the bib of FIG. 1 in a flat position;

FIG. 3 is a front perspective view of the bib of FIG. 1 in a wearing position; and

FIG. 4 is a front perspective view of a second embodiment of the bib in a wearing position and showing my new design.

I claim:

The ornamental design for a bib, as shown.
